UNITED STATES PATENT OFFICE.

EDWARD F. GLACKEN, OF BROOKLYN, NEW YORK.

BOTTLE.

Application filed November 29, 1924. Serial No. 752,869.

This invention relates to improvements in wide mouth bottles and more particularly milk or cream bottles.

Milk bottles, after filling, are deposited in 5 compartment boxes or racks from which they are delivered by the dealer or so-called milkman to his customers.

The bottles delivered are handled by the dealer or milkman at the neck below the lip 10 in removing them from and placing them in the box or rack. Such handling has resulted in serious loss due to breakage of filled and empty bottles and spilling of the contents of the filled bottles.

15 The reason for this loss is that, the bottle neck being smooth, the grip of the dealer's or milkman's hands thereon is insecure and the bottle is liable to and frequently does slip out of his hand.

20 This is particularly true of bottles handled by milkmen making deliveries to the houses on their milk routes. Such deliveries are made in the early morning and must also be made quickly so that the milk will be 25 delivered at all the houses on the route before a certain early morning hour, and, in the winter season, these deliveries are often made in the dark.

In making these deliveries the milkman 30 seizes the bottles by their necks below the lips thereon, removes them from the rack in his wagon, carries them in his hands to the house and deposits them there on a porch, shelf or other designated place. He 35 then takes from the porch &c. the empty bottles left there by the householder and carries them to his wagon, where he deposits them in the rack.

Frequently in removing the filled bottles 40 from the rack and carrying them to the house, and also in lifting the empty bottles from the porch, etc., and carrying them to and depositing them in the rack in his wagon, the bottles, because of the smoothness of their necks, slip from his hand and 45 are broken.

I have discovered that this loss may be avoided to a considerable extent by providing the bottle neck with gripping projections beneath the bottle lip, where, as just 50 stated, the milkman grips it, such projections preventing turning of the bottle in the milkman's hands and also its endwise movement therein.

55 I have also discovered that such projections are further useful to the milkman as

a means of identifying his bottles so that he can tell simply by touch whether or not empty bottles found by him on a porch or in making deliveries are his. This is of 60 considerable importance where deliveries are made in the dark, as they frequently are, because milk bottles are very much alike and a milkman cannot distinguish one empty bottle from another, and therefore cannot be 65 certain that he is taking only his own empty bottles, unless he has sufficient light to read the labels or names blown in the bottle.

According to the improvements of the present invention these hand-gripping and 70 bottle-identifying projections are formed on the bottle neck during the operation of molding the lip of the bottle.

In the accompanying drawing—

Figure 1 is a vertical elevation of a milk 75 bottle embodying the present invention in its preferred form.

Figure 2 is a sectional elevation of the upper portion of the same on an enlarged 80 scale.

Figure 3 is a horizontal section on the line 3 of Figure 2.

Referring to said drawings *a* represents the bottle body and *b* the lip thereof at the upper or pouring end of the bottle. 85

Beneath the lip *b* the bottle is provided with a plurality of hand-gripping projections *c* which are preferably vertical and are sufficient in number and of such shape and dimensions laterally, and in such proximity to each other, that they will, as a group, provide, at all points around the bottle neck, a secure grip for the hand.

The group of gripping projections *c* is, as best shown in Figure 2, within the vertical 95 plane of the lip *b*. By so arranging them, relatively to the lip, all danger of the projections being broken off or chipped by contact of one bottle with another is avoided.

The projections *c* are integral with the 100 bottle itself and are formed thereon during the operation of molding the bottle lip.

What I claim is:—

A wide mouth bottle having a laterally projecting lip with a smooth, unbroken pouring end and substantially vertical integral gripping projections crowded together below and inside the vertical plane of and in close proximity to said lip. 105

In testimony whereof, I have hereunto set 110 my hand.

EDWARD F. GLACKEN.
